Pratt A. Spicer, Inventor.

By his Attorney in fact:
Chas E. Barber.

UNITED STATES PATENT OFFICE.

PRATT A. SPICER, OF MARSHALL, MICHIGAN.

SPRING-TOOTH HARROW.

SPECIFICATION forming part of Letters Patent No. 398,858, dated March 5, 1889.

Application filed September 29, 1887. Renewed July 25, 1888. Serial No. 281,035. (No model.)

To all whom it may concern:

Be it known that I, PRATT A. SPICER, a citizen of the United States, residing at Marshall, in the county of Calhoun and State of Michigan, have invented a certain new and useful Improvement in Spring-Tooth Harrows, of which the following is so full, clear, and exact a description as will enable others skilled in the art to which my invention appertains to make and use the same, reference being had to the accompanying drawings.

My invention relates to an improvement in spring-tooth harrows, the object being to construct a simple and inexpensive holder or shoe for the harrow-tooth, which will serve the double purpose of a holder and a stop for the tooth, preventing its becoming broken under heavy strain and protecting its front edge from wear, and as a runner for the harrow, holding it up and protecting it from wear and at the same time preventing it from becoming loaded by earth.

My invention further consists in certain peculiarities in the construction, arrangement, and combination of parts, substantially as will be hereinafter described, and particularly pointed out in the claims.

In the accompanying drawings illustrating my invention, and in which similar letters of reference denote corresponding parts throughout the several views, Figure 1 is a perspective of a harrow embodying my invention. Fig. 2 is a detail representation of the spring-tooth holder, showing the tooth in position therein. Fig. 3 is a detail representation, in perspective, of the holder, showing its construction more clearly. Fig. 4 is a rear end elevation of the same, showing more clearly the slot for the reception of the harrow-tooth. Fig. 5 is a side elevation of the holder. Fig. 6 is a bottom view of the holder with a tooth secured thereto. Fig. 7 is a detail representation of that portion of the harrow-tooth formed with the series of graduated notches or marks. Fig. 8 is a modification of the holder or shoe. Fig. 9 is a detail of the bolt and plate.

A represents a harrow-frame, which may be of any suitable construction, and to which is attached a draw-bar, B, to which the motive power is adapted to be secured.

The spring-tooth holders C are adapted to be secured to the under side of the frame A, and they serve the double purpose of a holder and a guard for the tooth M and as a runner 55 for the harrow, preventing its running too deep and the frame from loading with earth on its top and becoming quickly worn out on its under side by heavily dragging on the surface of the ground. This holder or shoe is 60 the main feature of my invention, and is preferably formed slightly curved, in order to conform to the curvature of the tooth, and it is constructed on its outer side with a rib, D, running longitudinally and forming the runner proper 65 for the harrow. This holder C is formed also on its under side at one of its extremities with a downwardly-extending lug or projection, E, having flanges e e, and formed with a longitudinal slot, F, of a suitable size for the 70 reception of the harrow-tooth, and with a transverse recess, F', for the reception of the tooth-clamping device, to be hereinafter described. This holder or shoe C is secured to the harrow-frame, preferably by means 75 of the bolts f f, extending down through perforations formed in each side of the said holder and at suitable distances from the ends and down through perforations formed in the harrow-frame, and are secured to the 80 upper side of said frame by means of nuts g. The blunt end of the tooth is adapted to be inserted in the slot F, and is held securely therein from displacement by means of a set-screw, H, extending through a perforation formed in the harrow-frame, and carrying a plate, I, having a screw-threaded perforation, i, for the reception of the end of the 85 said set-screw H. This plate I is adapted to be situated on the under side of the harrow-frame, between it and the tooth, and within the recess F', and it is made of such size as to conveniently fit therein. Obviously, by turning this set-screw H in a certain direction its point will project out beyond the top 90 of the said plate and will come in contact with the tooth and bind it tightly against the shoe or holder, and by continuing to turn the said screw the plate will be crowded against the frame, and the tooth will thus be held so 100 tightly that it cannot move or become displaced.

The tooth, when under strain, will rest in the groove of the shoe or holder and will pry up under the lug cast on the upper side of the said shoe at its rear end, and, by reason of the fact that the said shoe or holder is bolted solidly to the frame of the harrow, the action of the tooth in labor is to cause it to lie down snugly to the bed of the tooth-holder, and this plate I and set-screw H have then no duty 5 to but to hold the tooth when released from strain and prevent it slipping back and forth.

When it is desired to change the set of any or all of the teeth, it is accomplished simply by turning the set-screw H with a wrench or 15 other suitable device, which releases the pressure upon the tooth, permitting it to be moved forward or backward, as the case may be, to cause the tooth to run shallower or deeper.

20 Referring to Fig. 8, which shows a modification of the holder or shoe, it will be observed that the lug E is formed simply with the longitudinal slot F, and the plate I, through which the screw II projects, is cast 25 solidly forward from the top of the lug which has the slot in it for the tooth, from the top part of the same, so as to have a solid flat surface where the shoe bolts up under the frame. Thus it will be obvious that this will 30 take the place of the loose plate I, and is formed with a slot for the set-screw, the same as the said plate I, and the tooth will be held in precisely the same manner as if the other form were employed. I have found 35 from experience that there is less trouble in inserting the tooth with this form of shoe.

I do not wish to be understood as limiting myself to the exact construction herein shown and described, as many of the details may be

varied at will without departing from the 40 general spirit of my invention or in any manner interfering with its usefulness.

Having now described the objects, uses, and advantages of my invention, and having described a preferred means of carrying the 45 same into effect, what I believe to be new, and desire to secure by Letters Patent, and what I therefore claim, is—

1. A spring-harrow-tooth holder having on its under side a rib forming a runner, its upper side provided with a slotted bearing-lug, and the set-screw and plate, all combined and adapted for use in connection with a spring harrow-tooth and its beam, as shown and described. 55

2. A spring-harrow-tooth holder consisting of rib forming a runner on its under side, its upper portion provided with a slotted and recessed bearing-lug, a plate, and a set-screw, in combination with a harrow-beam and a 60 spring harrow-tooth, as shown and described.

3. In a spring-harrow-tooth holder, the combination, with the harrow-beam, of a holder provided on its under surface with a rib forming a runner, the upper portion of said holder 65 provided with a slotted and recessed bearing-lug, and the spring-tooth passing through the slotted portion of the lug and connected to the holder, and also adjustable thereon by means of a set-screw connecting the harrow- 70 beam and holder, as shown and described.

In testimony whereof I affix my signature in the presence of two witnesses.

PRATT A. SPICER.
